UNITED STATES PATENT OFFICE.

CHARLES L. ZABRISKIE, OF NEW YORK, N. Y., ASSIGNOR TO CHARLES P. ROGERS AND COMPANY (INC.), A CORPORATION OF NEW YORK.

JACK.

Application filed December 5, 1924. Serial No. 754,005.

My present invention relates more particularly to so-called hydraulic jacks, which comprise piston and cylinder elements operated by hydraulic pressure of a liquid, usually oil, which is pumped into the cylinder space to force the operative expansion or lifting movement of the relatively movable parts and in the present device, the piston element is fixed and the cylinder element is the one forced upward by the liquid to produce the desired lifting effect. The invention was primarily designed for embodiment in a high power jack, in this case a 25-ton jack, and in such devices the relatively large amounts of liquid to be pumped and the enormous lifting pressures, make certain features of my invention highly desirable if not indispensable, but it will be evident that various of its novel features will be very useful although not so indispensable in jacks of less power.

In any jack where there is a relatively low power-work ratio, the hydraulic method of operation makes it easy to apply relatively great lifting effects by relatively small manual effort and such great and easily applied lifting effects are likely to make trouble at the end of the stroke where further expansion movement of the parts must be prevented. Heretofore mechanical stops have been employed as, for instance, a collar on the lifting plunger which at the upper end of the stroke engages a corresponding inwardly projecting flange on the stationary element. With such positive stops, undesirable strains are imposed on all parts of the structure, including the direct strain on the stop collar or flange and also back pressure on the pump and valves. Where the lifting power is sufficiently great and the power-work ratio sufficiently small, I have discovered that damaging mechanical strains are set up at various points in the apparatus and that continued hand operation of the pump after the end of lifting stroke of the parts will wreck almost any mechanical stop means that can be provided without exceeding convenient limits of strength and massiveness of the structure.

One feature of my present invention involves means for limiting the upward travel of the plunger element, by cutting off the power, instead of trying to block such movement by a mechanical stop means. I preferably predetermine the height to which the

plunger may rise and use the movement of the plunger itself to control the flow of working fluid to the pumps. In other words, the plunger at a predetermined point in its upward movement operates a valve to cut off the inlet to the pump.

A further feature of the invention is the use of a double acting manually operated pump for forcing the working fluid to the plunger. The double acting feature greatly speeds up operation without making the device more difficult to operate. The invention also comprehends various novel arrangements of ducts and controlling valves for the motive fluid, packings for the plunger and other structural details which will be more fully hereinafter set forth. The invention may be more fully understood from the following description in connection with the accompanying drawings, wherein—

Fig. 1 is a view mainly in side elevation of a jack embodying the invention, parts being broken away for clearness and the elevated position of the plunger being indicated in dotted lines;

Fig. 2 is a transverse sectional view of the line 2—2 of Fig. 1;

Fig. 3 is a plan view of the ball retaining disk;

Fig. 4 is a broken longitudinal section view on the staggered line 4—4 of Fig. 2;

Fig. 5 is a similar view on the line 5—5 of Fig. 2.

The jack includes a substantial base 10, preferably of cast iron, having a threaded socket 11 which receives the lower end of an upstanding cylindrical member 12, preferably a heavy drawn steel tube, forming the outer wall of the annular reservoir 13. Countersunk in the bottom of socket 11 is a second socket 14 also threaded and receiving threaded lower end of a similar cylindrical member 15 constituting a cylindrical guide member or guiding piston element upon which the cylindrical plunger 16 is telescopically mounted. The head 17 of the cylinder 16 is preferably in the nature of a plug threaded into the upper end of the plunger cylinder and including a marginal flange 18 which seats on a packing 19 disposed in a suitable groove in the outer end of the plunger cylinder. In addition to the threaded connection between the plunger head and plunger any other suitable means may be employed, to firmly lock the head.

in place and to prevent leakage of the working fluid under the flange 15.

The reservoir space 13 is closed at the top by annular cap 20 which threads into the upper end of cylindrical casing member 12 and is provided with a central opening 21 to accommodate the plunger. The inner wall of this opening is cut away to provide a bevelled shoulder at 22, cooperating with a screw bushing 23 to retain and compress packing 24. The packing is wedged between the shoulder and the bushing and insures the firm non-leak, sliding contact with the plunger. The cap 20, bushing 23 and packing 24 have a guiding and oil wiping function which is more important than their function of preventing leakage since in normal operation there is very little internal pressure within the reservoir.

20 In the top of the guide cylinder 15 is a screw plug 25 having a central opening 26 affording an unrestricted passage for the oil or other working fluid from the interior of the guide member to the under surface of 25 the plunger head. The passage 26 extends through an upwardly projecting externally threaded boss 27 encircled by radial and cup leather washers 28 and 28^a, retained in place by a rigid cup shaped expander 29 which 30 is in turn firmly jammed against the washers 28 by nut 30 threaded on the extension boss 27. One of the washers is of greater diameter than the guide cylinder 15 and the cup washer has the usual flexible portion 31 which is turned upwardly and confined between the flange 29^a on the washer 28 and the interior wall of the plunger to provide a 35 wiping packing surface of appreciable width to prevent escape of the oil from the hydraulic pressure space, back into the reservoir 13, through the sliding joint between cylinders 15 and 16.

30 The two pump cylinders 35 are formed by boring vertical holes in a lateral extension 36 of the base 10. Plunger pistons 37 work in the cylinders 36, said plungers passing through bushings 38, which are screwed into the enlarged upper ends of the cylinders and serve to retain and compress packings 39.

45 Tendency to leak around the piston plungers may be further checked by the use of cupped flexible washers 40 secured to the lower ends of the pistons by screws 41. A rocker bar 42 is fulcrumed midway between 50 the pump cylinders on a stud 43 mounted in an upward projection 44 of the base member. To connect the rocker 42 with the pistons, I employ connecting links 45, the lower ends of which are pivotally secured in the 55 bifurcated upper ends 46 of the piston rods by pivot pins 46^a, and the upper ends of the links are bifurcated at 47 to straddle the ends of the rocker bar to which they are 60 pivotally connected as by pivot pins 48^a. An 65 extension 49 at one end of the rocker is

adapted to permit the attachment of an elongated hand lever 50 for manually operating the two single acting pumps.

The means for delivering oil from the reservoir 13 to the cylinders of the pumps 70 includes a well 52 in the bottom of the socket 11 having an enlarged upper end 53 accommodating a screw plug 54 providing a downwardly facing valve seat 55. The valve stem 56 projects through the opening in the valve 75 seat and carries a valve 57 of brass, steel or some other material which will tightly seat when the valve stem is vertically shifted. The means for lifting the valve to prevent oil from running from the reservoir into 80 the well includes a member having lost motion engagement with the plunger, preferably in the form of a ring 58 on the upper end of stem 56, encircling plunger 16 near the upper end of travel of the lower portion 85 thereof. The ring 58 is adapted to be engaged by radially projecting pins 59 secured to the plunger adjacent its lower end, and when the plunger is moved to its elevated position indicated in dotted lines 51, pins 90 59 will have picked up the ring 58, shifted the valve stem 56, closed the valve and cut off oil supply from the reservoir to the pump. The position of the ring, pins and valve at this time are also indicated in dotted 95 lines in Fig. 1, but the lost motion may be considerably greater than indicated.

From the bottom of the well 52 which supplies both the pump cylinders, a pair of diverging oil passages 60 of relatively small 100 cross section, lead to the respective cylinders 35. Passages 60 communicate with inlet valve seats 61 below the respective pump cylinders, on which inlet ball checks 62 normally seat by gravity. It is desirable to provide wires or projections 80^a disposed centrally of the passages 60 and anchored in closure plugs 80 at the outlets of the passages, such wires serving as cages for these ball valves to limit the extent to which they 110 are elevated off their seats on the intake strokes of the pump pistons. The plugs and wires are readily removable for cleaning purposes.

Oil ducts 63 connect the bottoms of the 115 cylinders 35 with the interior of the cylindrical guide member 16 converging somewhat toward their discharge ends so that the two sets of passages 60, 63 are arranged substantially in the shape of a double V as 120 seen best in Fig. 2. With this arrangement, the intakes of both pumps can be controlled by a single cut off valve 57. A circular plate 64 secured to the bottom of the socket 14 by screw 65 is formed with slotted inlet 125 openings 66 above the outlets of the oil passages 63, these openings being sufficiently narrow to serve as ball retainers preventing ball check valves 67 from being forcefully ejected from their seats during forcing 130

strokes of the pumps. Check valves 67 are of course intended to prevent back flow of oil from the interior of the guide cylinder and plunger during suction strokes of the pumps and also to hold the load after it has been lifted.

The outlet passage 70 through which oil is released and returned to the reservoir to permit lowering of the plunger to its normal position, includes a vertically disposed intake portion 71 registering with an opening 72 in cage plate 64. Passage 70 is controlled by a needle valve 73 having threaded adjustment in a bushing 74 which is screwed into the base member, suitable packing 75 being used around the valve. The valve is manually adjustable by the handle 76 and works against a seat 77 in the passage 70. When the valve is retracted as shown in Fig. 4, passage 70 is placed in communication with a vertical return passage 78 to the reservoir.

In normal operation of the device, it is obviously necessary that the needle valve 73 be closed before the pump is operated, otherwise there can be no substantial pressure maintained within the plunger and its guide. With the needle valve closed and the pump in operation, oil is sucked from the reservoir through passages 60 and into the pump cylinders on the intake strokes of the pump pistons. On the expelling strokes of such pistons ball checks 62 prevent back flow to the reservoir and the oil is expelled through passages 63 around ball checks 67 into the interior of the plunger guide, checks 67 preventing any back pressure from the interior of the plunger being transmitted to the pump cylinders. After the lifting plunger has been raised by the hydraulic pressure of the motive fluid therein to the point which is predetermined by the position of the pins 59 and the length of the valve stem 56, the pins will pick up the ring 58 and close the valve 57 to cut off the supply of oil to the pump. Each pump will then idly draw a vacuum on the intake stroke and release the same on the forcing stroke and these strokes being correlative for the two pumps will balance and there will be substantially no load on the pump handle. Practically this operates a most effective signal to the operator that the jack has reached the end of the lift. One advantage of control of the intake is that the valve 57 cannot be subjected to a strain greater than the fifteen pounds per square inch represented by a perfect vacuum, whereas the strain on a similar valve arranged to block discharge from the pumps is limited only by the power and design of the parts and is always enormously greater. The advantage of two pumps in opposite phase affording the above described balanced-vacuum, no-load condition, is obvious.

With a mechanical stop for the plunger as in the old types of jacks, the operator frequently fails to notice the added strain on the handle until the stop has been severely strained or the plunger blown completely out of the reservoir.

To effect return of the plunger to its normal telescoped position on the guide, it is merely necessary to manually open the needle valve 76 and the weight of the load 75 or other pressure on the plunger will expel the oil through passages 71, 70, 78 into the reservoir until the lowermost position is reached.

The use of the double acting pump involves no increase in the maximum manual effort because the additional work is done on the up-stroke of the handle and it has the advantage that it doubles the speed with which the load may be lifted. I entirely eliminate the possibility of straining the jack or blowing the lifting plunger out of the reservoir by doing away with all mechanical plunger checking devices and causing the plunger to automatically cut off the supply to the pumps so that they draw a vacuum when the plunger has risen to a predetermined height. The valve stem 56 may be easily made adjustable in length so that its height may be predetermined in accordance with the particular work to be done by the jack, but I find that for all ordinary purposes, an approximately constant length of valve stem, set for maximum height will answer the purpose. As the valve must be closed tightly, it is highly desirable that there should be substantial yield somewhere between the powerful lifting means and the valve seat and preferably the stem 56 is made in two sections as indicated, with a very stiff connecting spring 56^a between them whereby the valve 57 may be seated as powerfully as desired without danger of tearing the valve off the stem or bending ring 58 out of horizontal.

With the lifting plunger in its normal telescoped position, the weight of the ring 58, stem 56 and valve 57 may rest upon a bevelled stop 57^a in the passageway 52, keeping the valve away from its seat 55, but not preventing inlet of oil from the force pump; or the ring 58 may seat upon pins (not shown) projecting inwardly from the walls of the reservoir, thereby holding the valve in the midway position shown in Fig. 5.

With oil or other working fluid under high pressure on the inside of the plunger guide and plunger, there are only three possible points where leakage might occur and in every instance, this possibility is minimized by the nature of the sealing device used. Leaking of the oil around the plunger head 17 is practically prevented by the threaded connection between the head and plunger and the packing 17. Oil pressure

in the top of the plunger above the packings 28 will tend to more firmly force the portion 31 of the upper washer against the wall of the plunger. Furthermore, the plunger and its guide are carefully fitted so that the possibility of leakage around the outside of the guide member 15 is remote. If the offtake valve 73 and its seat 77 are properly mated, there is little or no chance of oil escaping back to the reservoir. If there should be a slight leakage either past valve 73 or around outside of the guide, the escaping oil would be directed back into the reservoir.

Although I have shown an embodiment of 15 the invention which makes use of a single telescoping lifting plunger, it will be obvious that any number of plunger sections telescoping one upon the other, might be employed.

20 I claim:

1. A hydraulic jack, including a hydraulically operated lifting plunger, a pump for forcing working fluid under the plunger to lift the same, and means controlled by the 25 plunger for automatically cutting off the supply of working fluid to the pump when the plunger has moved a predetermined distance.

2. A hydraulic jack, including a hydraulically operated lifting plunger, a pump for forcing working fluid under the plunger to lift the same, and means controlled by the plunger for automatically cutting off the supply of working fluid to the pump when 30 the plunger has moved a predetermined distance, said means including a valve controlling the supply of working fluid to the pump and means carried by the plunger operable to close the valve.

3. A hydraulic jack, including an oil reservoir, a hollow plunger guide mounted centrally of the reservoir, a lifting plunger sliding on the guide, a pump for pumping oil from the reservoir into the hollow plunger guide and under the head of the plunger 45 to effect elevation of the same, and means for cutting off the oil supply when the plunger has travelled a predetermined distance.

4. A hydraulic jack, including an oil reservoir, a hollow plunger guide mounted centrally of the reservoir, a lifting plunger sliding on the guide, a pump for pumping oil from the reservoir into the hollow plunger guide and under the head of the plunger 55 to effect elevation of the same, and means controlled by the plunger for cutting off the oil supply when the plunger has risen to a predetermined height.

5. A hydraulic jack, including an oil reservoir, a hollow plunger guide mounted centrally of the reservoir, a lifting plunger sliding on the guide, a pump for pumping oil from the reservoir into the hollow plunger 60 guide and under the head of the plunger

to effect elevation of the same, a valve controlling the flow of oil from the reservoir to the pump, operating means for the valve, and means on the plunger engageable with said operating means to close the valve when 70 the plunger has travelled a predetermined distance.

6. A hydraulic jack, including an oil reservoir, a hollow plunger guide mounted centrally of the reservoir, a lifting plunger 75 sliding on the guide, a pump for pumping oil from the reservoir into the hollow plunger guide and under the head of the plunger to effect elevation of the same, means for cutting off the oil supply automatically when the plunger has travelled a predetermined distance, and separate manually operable means for permitting return of oil to the reservoir.

7. A hydraulic jack, including a base, a 85 hollow member mounted on the base and constituting an oil reservoir, a hollow plunger guide disposed centrally of the reservoir, a lifting plunger sliding on the guide, means for pumping a liquid lifting medium from the reservoir into the guide under the piston, said means including a pair of cylinders in the base, pistons working in the cylinders, a rocker arm having its opposite ends operatively connected to the pistons. 90

8. A hydraulic jack, including a base, a hollow member mounted on the base and constituting an oil reservoir, a hollow plunger guide disposed centrally of the reservoir, a lifting plunger sliding on the guide, means for pumping a liquid lifting medium from the reservoir into the guide under the piston, said means including a pair of cylinders in the base, pistons working in the cylinders, a rocker arm having its opposite ends operatively connected to the pistons, said base having diverging passageways therein leading from the reservoir to the pistons, a single valve controlling both of said passageways and converging passageways leading from 100 the pump cylinders to the interior of the plunger guide. 105

9. A device of the class described in claim 8, wherein the lifting plunger includes 110 means for controlling the valve.

10. A hydraulic jack, including a base, a hollow member mounted on the base and constituting an oil reservoir, a hollow plunger guide disposed centrally of the reservoir, a lifting plunger sliding on the guide, means for pumping a liquid lifting medium from the reservoir into the guide under the piston, said means including a pair of cylinders in the base, pistons working in the cylinders, a rocker arm having its opposite ends operatively connected to the pistons, said base having diverging passageways therein leading from the reservoir to the pistons, a single valve controlling both of said passageways and converging passageways lead- 115 120 125 130

ing from the pump cylinders to the interior of the plunger guide, a valve stem for the controlling valve, operating means for the stem, and pins on the lifting plunger engageable with said operating means to close the valve and cut off the oil supply to the pump cylinders when the plunger has risen to a predetermined height.

11. A hydraulic jack, including a base, a hollow member mounted on the base and constituting an oil reservoir, a hollow plunger guide disposed centrally of the reservoir, a lifting plunger sliding on the guide, means for pumping a liquid lifting medium from the reservoir into the guide under the piston, said means including a pair of cylinders in the base, pistons working in the cylinders, a rocker arm having its opposite ends operatively connected to the pistons, and means for automatically cutting off the supply of oil to the pumps when the lifting plunger has risen to a predetermined height.

12. A hydraulic jack, including a base member having a socket therein and a countersunk portion in the bottom of said socket, a cylindrical member fitted into the socket and constituting the outer wall of an oil reservoir, a cylindrical guiding member secured in the countersunk portion of the socket and constituting the inner wall of said reservoir, a lifting plunger slideable on the cylindrical guide, a pump including a pair of pumping cylinders formed in the base, pistons in said cylinders, a rocker arm having its ends connected to the pistons, said base having diverging one way oil passages therein leading from the reservoir to the pump cylinders and one way converging oil passages therein leading from the pump cylinders to the interior of the guide member.

13. A hydraulic jack, including a base member having a socket therein and a countersunk portion in the bottom of said socket, a cylindrical member fitted into the socket and constituting the outer wall of an oil reservoir, a cylindrical guiding member secured in the countersunk portion of the socket and constituting the inner wall of said reservoir, a lifting plunger slideable on the cylindrical guide, a pump including a pair of pumping cylinders formed in the base, pistons in said cylinders, a rocker arm having its ends connected to the pistons, said base having diverging one way oil passages therein leading from the reservoir to the pump cylinders and one way converging oil passages therein leading from the pump cylinders to the interior of the guide member, and a common valve for controlling the flow of oil from the reservoir to the cylinders through said first mentioned passages.

14. A hydraulic jack, including a base member having a socket therein and a countersunk portion in the bottom of said

socket, a cylindrical member fitted into the socket and constituting the outer wall of an oil reservoir, a cylindrical guiding member secured in the countersunk portion of the socket and constituting the inner wall of said reservoir, a lifting plunger slideable on the cylindrical guide, a pump including a pair of pumping cylinders formed in the base, pistons in said cylinders, a rocker arm having its ends connected to the pistons, said base having diverging one way oil passages therein leading from the reservoir to the pump cylinders and one way converging oil passages therein leading from the pump cylinders to the interior of the guide member, and manually controlled means for permitting the return of oil from the interior of the guide member to the reservoir.

15. A hydraulic jack, including a base member having a socket therein, and having a central countersink in the bottom of said socket, a cylindrical member secured within the socket and constituting the outer wall of an oil reservoir, a cylindrical plunger guide member secured in the countersunk portion of said socket and constituting the inner wall of said reservoir, a lifting plunger slideable on the guide, a cage plate secured to the bottom of the countersink within the cylindrical guide member, a pump for delivering oil from the reservoir to the interior of the guide member, including an oil delivering passage terminating under the cage plate and having a ball check at its delivery end, said cage plate having a slot therein to permit the passage of oil therethrough and retain the ball check in the end of the passage.

16. A hydraulic jack, including an oil reservoir, a lifting plunger and two single acting pumps for delivering oil from the reservoir under the plunger, said pumps including a pair of pump cylinders, pistons in the cylinders, a rocker bar pivoted adjacent its centre, and connecting rods, operatively connecting the ends of the rocker bar to said pistons, the axes of said pump cylinders and pistons and the plane of movement of the rocker bar being approximately parallel with the axis of the reservoir and approximately perpendicular to a radius thereof.

17. A hydraulic jack, including an oil reservoir, a lifting plunger and two single acting pumps for delivering oil from the reservoir under the plunger, said pumps including a pair of pump cylinders, pistons in the cylinders, a rocker bar pivoted adjacent its center, and connecting rods, operatively connecting the ends of the rocker bar to said pistons, said pistons including bifurcated upper ends straddling and pivotally connected to the lower ends of the connecting rod, the axes of said pump cylinders and pistons and the plane of movement of the rocker bar being approximately parallel

with the axis of the reservoir and approximately perpendicular to a radius thereof.

18. A hydraulic jack, including an oil reservoir, a lifting plunger and two single acting pumps for delivering oil from the reservoir under the plunger, said pumps including a pair of pump cylinders, pistons in the cylinders, a rocker bar pivoted adjacent its center, and connecting rods, operatively connecting the ends of the rocker bar to said pistons, said pistons including bifurcated upper ends straddling and pivotally connected to the lower ends of the connecting rod, said connecting rods including bifurcated upper ends straddling and pivotally connected to the ends of the rocker bar, the axes of said pump cylinders and pistons and the plane of movement of the rocker bar being approximately parallel with the axis of the reservoir and approximately perpendicular to a radius thereof.

19. A hydraulic jack, including a base having a socket therein, a cylindrical member secured within the socket and constituting the outer wall of an oil reservoir, a concentrically disposed internal cylindrical guide member constituting the inner wall of said reservoir, a lifting plunger sliding on the inner cylindrical member, a pump for delivering oil from the reservoir to the interior of the inner member, under said piston, said base member having oil passages

therein for delivering oil from the reservoir to the pump and from the pump to the socket, ball checks in the discharge ends of said oil passages and a cage plate in the socket limiting the movement of said ball checks.

20. A hydraulic jack, including an oil reservoir, hollow relatively extensible cylinder and piston members telescoping one upon the other and adapted to be relatively extended by pumping oil therewithin, a pump for delivering oil from the reservoir to the members, means controlled by relative movement of said members for cutting off the oil supply to the pump when said members have been relatively extended a predetermined distance.

21. A hydraulic jack, including an oil reservoir, hollow relatively extensible cylinder and piston members telescoping one upon the other and adapted to be relatively extended by pumping oil therewithin, a pump for delivering oil from the reservoir to the members, means controlled by relative movement of said members for rendering the pump inoperative to deliver oil to said members when they have been relatively extended to a predetermined extent.

Signed at New York in the county of New York and State of New York this third day of December, A. D. 1924.

CHARLES L. ZABRISKIE.
